FASTENING AND SECURING MEANS

George W. Gail, Ruxton, Md.

Application March 2, 1934, Serial No. 713,757

8 Claims. (Cl. 306—38)

This invention relates to fastening and securing means and has particular reference to providing effective means for securing tool heads to their handles and securing the rungs of chairs, stools or other articles of furniture to the legs connected thereby.

Attempts have heretofore been made to provide effective securing mechanism for these purposes, and in the case of tools, it has been proposed to bore a longitudinal hole in the handle and to provide a metal tie-rod in this bore. This requires drilling an aperture of unusual length in the handle, an operation which has proved slow, expensive, difficult, impractical, unsatisfactory and unreliable. If the bore or hole is too large the handle is weakened too much. If the bore is small enough so as not to weaken the handle appreciably, the drilling of a hole of such small cross-section is unsatisfactory and impractical owing to the tendency of the drill or bit to break and bend and the inability to accurately control the boring due to the variations in the grain of the wood, which grain is rarely exactly parallel to the center line of the desired bore. Also, where varying degrees of hardness are met, further difficulty in drilling an accurate hole results.

Among the objects of this invention is the provision of a means for overcoming the objections heretofore noted and to accomplish these results in a cheap, efficient and satisfactory manner.

Other, further and more specific objects of this invention will become readily apparent to persons skilled in the art from a consideration of the following description when taken in conjunction with the accompanying drawings, wherein:

Fig. 1 is a side elevation showing the application of my invention to a hammer, a portion of the device being broken away for clearer illustration of the mechanism.

Fig. 2 is an elevation of the hammer shown in Fig. 1, taken at right angles to the latter view.

Fig. 3 is a top plan view of the hammer shown in Fig. 1.

Fig. 4 is a bottom plan view of the handle shown in Fig. 1.

Fig. 5 is a detail, fragmental view of the handle shown in Fig. 1, illustrating means for preventing separation of the parts of the handle from each other.

Fig. 6 is a cross-section along line 6—6 of Fig. 1.

Fig. 7 is a side elevation showing the application of my invention to a hatchet or ax employing a curved handle.

Figs. 8, 9, and 10 are cross-sections taken along lines 8—8, 9—9 and 10—10, respectively, of Fig. 7.

Fig. 11 is a cross-section of a handle illustrating a modified form of my invention.

Fig. 12 illustrates diagrammatically a chair to which my invention may be applied.

Fig. 13 is a detail, fragmental view showing the application of my invention to the legs and rungs of a chair such as shown in Fig. 12.

Fig. 14 is a cross-section along line 14—14 of Fig. 13.

The hammer shown in Figs. 1 to 6 comprises the head 2 provided with the opening 4 into which the handle 6 projects. This handle 6, usually made of wood, is formed of two parts 8 and 10 connected to each other longitudinally, the longitudinal faces on each part preferably forming a union 12 which is in a plane passing through the axis of the handle, and when the handle is of elliptical cross-section, as shown in Fig. 6, this union 12 preferably passes through the locus of the major axes of the cross-sections. The parts of the handle may be formed by first turning a handle to the desired size and then sawing the handle longitudinally into two parts along the proper plane. If desired, these conjugate parts 8 and 10 may be otherwise constructed and the conjugate parts assembled to form the desired construction. Each of these parts 8 and 10 are provided with central grooves 14 and 16 so that when these parts 8 and 10 are properly assembled the grooves will form a continuous, substantially axial bore through the handle. The cross-sections of the grooves may be varied to meet the particular needs and fancy, so as to form apertures having cross-sections which are circular, elliptical, polygonal or of other regular or irregular configuration. When desired, the size and shape of the cross-section of the aperture may be varied in different parts of the aperture.

After these parts 8 and 10 have been grooved, they can then be either glued together to hold same in proper alignment and against separation from each other or, if desired, other means for preventing separation may be employed, such as a tape 18 or the metal end cap 20. The head 2 into which the handle projects also aids in preventing separation of the parts of the handle at that end. The handle 6 is re-

cessed at 22 to accommodate the cap 20 and is also cut down at 24 in order that the outer surface of the annular flange 26 of the cap 20 will be continuous with the surface of the handle 6.

A rod 28, preferably of metal, passes through the bore 16 at the tool head end of the handle. This rod is attached to a cap or plate 30, and in Fig. 1 is shown threaded in the plate. The plate 30 rests upon the shoulder or abutment 32 in the tool head 2. A clearance is preferably provided between the handle 6 and the cap or plate 30. At the bottom of the handle, the other end of the rod 28 projects beyond the central bore and through the cap 20. A washer 34 is provided between the cap 20 and the nut 36. By tightening the nut 36 the handle 6 will be drawn tightly and securely held against the tool head in the opening 4, which is usually tapered, and the tool head will be prevented from flying off the handle because of any loosening of the parts. If desired, the plate 30 may be so threaded that the rod will tighten itself therein when the nut 36 is being tightened at the other end of the rod 28.

In applying my invention to a tool having a curved handle, such as shown in Fig. 7, certain modifications have been found desirable. It will be noted that when a tie-rod of circular or elliptical cross-section is employed with a curved handle and the handle is tightened against the tool head by tightening the nut at the open end of the handle, there is a tendency for the tie-rod to effect separation of the parts of the handle, due to pressure at the curves of the grooves. In order to counteract this tendency, I flatten the tie-rod at the curved portion 38 and shape the grooves to properly accommodate the flattened rod as will be evident by reference to Fig. 9. It will be seen from Figs. 8 and 10 that the rod 28 is circular near the ends of the handle while in the central portion it is flat as shown in Fig. 9.

The flattening of the intermediate portion enables the rod to bend more easily around the curves and also affords a good bearing area at the curves, thereby avoiding crushing of the fibers of the wood, which would cause a loosening of the tie-rod. In order to assure proper tightening under all conditions and to allow for the drawing together of the handle and the tool head, the bore is preferably increased in size at 40 and 42 so as to accommodate the parts of the tie-rod of either circular or flattened structure.

In the construction shown in Figs. 1 to 10 the members of the handle are joined at the plane passing through the locus of the major axes of the cross-sections. This construction is preferred because in most cases the extra strength to the handle afforded by this arrangement is desirable. However, in some instances, my invention may also be employed to advantage by having the parts of the handle constructed not of halves but of complementary parts differing in shape from each other. Such a construction is illustrated in Fig. 11 where the cross-section of the part 44 is a smaller sector of the ellipse than that of part 46. Also, my invention may be employed to advantage with handles wherein the tie-rod is positioned at a distance from the axis.

My invention is also applicable to the fastening and securing of rungs of a chair to the legs as shown in Fig. 13. In this case, the rungs

are formed of two parts 48 and 50 which are grooved to accommodate the tie-rod 52. The legs 54 are recessed at 56 to receive the washers 58 and nuts 60. The legs 54 are also recessed at 62 to receive the ends of the rungs comprising the sections 48 and 50. These rungs are positioned so that the plane between the parts 48 and 50 is vertical, because such arrangement adds to the strength and appearance. In this construction the rung serves as a strut and the tie-rod 52 as a tension member. After the rung and tie-rod have been positioned and tightened against the legs, the cavities or recesses containing the washers 58 and nuts 60 may be filled with putty or other filler so that the legs of the chair will present a smooth and neat finish.

The parts 48 and 50 of the rung may be glued together if desired, although generally the tight fit of the ends of the rungs in the recess 62 of the legs 54 is sufficient to keep the parts from separating. By this construction a reliable means is provided for maintaining the legs of a chair or other article of furniture against separating and loosening from the rungs.

My invention is not only applicable to numerous other tools and articles of furniture than specifically illustrated herein, but may also be appropriated to advantage for many other uses; for example, golf clubs and other articles having parts that have a tendency to loosen and become disengaged from each other.

In the claims, the term "nut" is employed to cover various forms of mechanical nuts including those having the hole extending partially through, those having the hole extending entirely through, those having the hole partially threaded and those having the hole entirely threaded.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims.

I claim as my invention:

1. In combination, a member having an opening therethrough, another member fitting into said opening, said latter member comprising two parts joined to each other lengthwise, each of said parts having a longitudinal groove, said grooves being disposed adjacent to each other and forming a longitudinal, substantially central passageway through said second member, and means for securing said members to each other, said means comprising a tie-member threaded at each end and passing through the longitudinal passageway of the second named member and projecting into the opening of the first named member, a nut on each end of said tie-member and means for securing said nuts in fixed relation to each other.

2. In combination, a tool head having an opening therethrough, a handle having an end extending into said opening, said handle comprising two parts joined to each other lengthwise, each of said parts having a longitudinal groove, said grooves being disposed adjacent to each other and forming a longitudinal, substantially axial passageway through said handle, means for preventing separation of said parts from each other, a tie-rod threaded at each end, disposed within said longitudinal passageway and

holding the tool head and handle together, said tie-rod projecting into the opening of the tool head, a nut on each end of said tie-rod and means for securing said nuts in fixed relation to each other.

3. In combination, a tool head having an opening therethrough, a handle having an end extending into said opening, said handle comprising two conjugate parts joined to each other lengthwise by their longitudinal faces, each of said parts having a longitudinal groove, said grooves being disposed adjacent to each other and forming a longitudinal, substantially central passageway through said handle, means for preventing separation of said conjugate parts from each other, a tie-rod threaded at each end, disposed within said longitudinal passageway and holding the tool head and handle together, said tie-rod projecting into the opening of the tool head, a nut on each end of said tie-rod and means for securing said nuts in fixed relation to each other.

4. In an article of furniture, in combination, a leg, a rung having an end projecting into said leg, said rung comprising two parts joined to each other lengthwise, each of said parts having a longitudinal groove, said grooves being disposed adjacent to each other and forming a longitudinal passageway through said rung, means at the other end of said rung for holding said parts of said rung together and a tie-rod within said longitudinal passageway and holding said rung and leg together.

5. In an article of furniture, in combination, a leg, a rung having an end projecting into said leg, said rung comprising two conjugate parts joined to each other lengthwise by their longitudinal faces, each of said parts having a longitudinal groove, said grooves being disposed adjacent to each other and forming a longitudinal, substantially central passageway through said rung, means at the other end of said rung for holding said parts of said rung together and a

tie-rod within said longitudinal passageway and having its ends projecting beyond said passageway and holding said leg and rung together.

6. In an article of furniture, in combination, a pair of legs, a rung disposed between said legs and having its ends projecting into said legs, said rung comprising two parts joined to each other lengthwise, each of said parts having a longitudinal groove, said grooves being disposed adjacent to each other and forming a longitudinal, substantially central passageway through said rung and a tie-rod within said longitudinal passageway and holding said rung and legs together, said rung serving as a strut and said tie-rod as a tension member.

7. In combination, a member having an opening therethrough, another member inserted in said opening, said latter member comprising two parts joined to each other lengthwise, each of said parts having a longitudinal groove, said grooves being disposed adjacent to each other and forming a longitudinal passageway through said second member, a tie-member threaded at each end, disposed within said longitudinal passageway and holding said members together, said tie-member projecting into the opening of the first named member, a nut on each end of said tie-member and means for securing said nuts in fixed relation to each other.

8. In combination, a tool head having an opening therethrough, a handle inserted in said opening, said handle comprising two parts joined to each other lengthwise, each of said parts having a longitudinal groove, said grooves being disposed adjacent to each other and forming a longitudinal passageway through said handle, a tie-rod threaded at each end, disposed within said longitudinal passageway and holding the tool head and handle together, said tie-rod projecting into the opening of the tool head, a nut on each end of said tie-rod and means for securing said nuts in fixed relation to each other.

GEORGE W. GAIL.
